UNITED STATES PATENT OFFICE.

LEE ROY SPOONER AND PAUL L. GRAY, OF WATERTOWN, SOUTH DAKOTA.

COIN-CONTROL LOCK FOR VENDING MACHINES.

Application filed March 21, 1923. Serial No. 626,606.

To all whom it may concern:

Be it known that we, LEE ROY SPOONER and PAUL L. GRAY, citizens of the United States, residing at Watertown, in the county 5 of Codington and State of South Dakota, have invented certain new and useful Improvements in Coin-Control Locks for Vending Machines, of which the following is a specification, reference being had to 10 the accompanying drawings.

This invention relates to coin control locks for vending machines.

An important object of the invention is to provide a device of this character by 15 means of which the ejector plunger is positively locked against operation until the proper coin is inserted, whereby release of the lock by jarring or tipping the vending mechanism is prevented.

20 A further object of the invention is to provide a device of this character which is simple in its construction and operation, durable in service and a general improvement in the art.

25 These and other objects we attain by the construction and arrangement shown in the accompanying drawings, wherein for the purpose of illustration is shown a preferred embodiment of our invention and 30 wherein like reference characters designate like parts throughout.

In the drawings:—

Figure 1 is a sectional view through a vending apparatus showing a lock mechanism constructed in accordance with our invention;

Figure 2 is a view similar to that shown in Figure 1, the side plate being removed and illustrating in dotted lines the manner 40 in which the lock plate limits the movement of the plunger.

Figure 3 is a fragmentary detailed view similar to that shown in Figure 2 and illustrating the manner in which the lock plate 45 is released upon insertion of the proper coin;

Figure 4 is a detailed sectional view showing the manner of constructing the tip-out opening and of operation during passage 50 of a coin of the proper denomination; and

Figure 5 is a similar view somewhat enlarged showing the discharge of a coin of smaller size.

Referring now more particularly to the 55 drawings, the numeral 10 indicates the front

wall of the vending machine and more particularly the front wall proper or a false front wall positioned behind the main front of a machine. Secured to the rear face of the front wall 10 a pair of substantially vertical parallel walls 11 and 12 are secured at their forward ends to the front wall 10. The walls 11 and 12 are substantially vertical or slightly inclined as more clearly shown in Figure 4 the purpose of this inclination appearing hereinafter. The wall 11 which has its outer face obtuse to the horizontal will hereinafter be referred to as the obtuse wall, and the wall 12, which has its outer face acute to the horizontal, 65 will hereinafter be referred to as the acute wall.

Secured to the obtuse wall 11 is a plate 13, the lower edge of which is approximately horizontal and at its rear edge a vertical 75 spacer and stop 14 is applied to the plate 13 filling the space between the plate 13 and the adjacent face of the acute wall 12. Likewise secured to the plate 13 is a triangular plate 15, the lower edge of which 80 coincides with the lower edge of the plate 13, the forward edge of which abuts the wall 10 and the upper edge of which inclines downwardly toward the lower end of the plate 14, the apex at the juncture of 85 the upper and lower edges of the plate being spaced relative to the adjacent edge of the plate 14 to provide a passageway 16. While the plate 15 is here described as triangular it may be notched out to V-form 90 as indicated to reduce the weight thereof. The plate 15 likewise fills the space between the plate 13 and the adjacent face of the acute wall 12 and the upper surface thereof forms a runway for coins inserted in the machine, the wall 10 being provided with an opening 17 through which a coin may be inserted to roll down the inclined upper face of the plate.

Secured to the obtuse wall 11 in spaced 100 relation to the lower edge thereof is a horizontally extending strip 18 of approximately the same thickness as the plate 13. To the forward end of this strip 18 is secured a spacer plate 19 having its upper surface 105 flush with the upper surface of the strip 18 and to the rear end of the strip 18 a similar plate 20 is provided, the forward end of the plate 20 being spaced from the rear end of the plate 19 so as to provide between the 110

face of the strip 18 and acute wall 12 and between the adjacent ends of the spacer strips 19 and 20 a coin discharge slot 21.

By this construction, between the lower 5 end of the plate 13 and the spacer plates 14 and 15 and the upper surface of the strip 18 and spacer plates 19 and 20, a guideway or channel 22 is formed in which is slidably mounted a plunger 23, the forward 10 end of which projects through the front plate 10 through an opening 24 formed therein and is adapted as at 25 for engagement with the handle for operation. The plunger is of substantially the same thickness as the plate 13 and strip 18 and adjacent its rear end is provided with an enlargement 26 forming an abutment slidably engaging the adjacent face of the acute wall 12, the enlargement 26 being provided 15 at its forward end and at the upper edge thereof with a forward extension 27. Projecting outwardly from the face of the plunger forwardly of and in spaced relation to the enlargement 26 is a second abutment 20 at its forward end and at the upper edge thereof with a forward extension 27. Projecting outwardly from the face of the plunger forwardly of and in spaced relation to the enlargement 26 is a second abutment 25 member 28.

The rear end of the plunger is provided with an ejector or ejector operating member 29 and this plunger when in its rear-most position has a forward end of the extension 27 of the enlargement 26 approximately aligned with the forward edge of the spacing strip 14. Slidably abutting the plunger between the abutments 26 and 28 is a floating lock plate 30 substantially rectangular in form and provided upon the upper end of the rear edge thereof with a rearward extension 31 and upon its lower edge at the rear end thereof the plate has a downwardly extending lug or tooth 32 adapted 35 for engagement in one of a series of notches 33 formed in the upper edge of the forward end of the spacer plate 20. This floating lock plate is freely movable in the space between the adjacent faces of the plunger 23 and the acute wall 12 and between the lower edge of the plate 15 and the plates 19 or 20, as the case may be, depending upon the 40 position of the lock plate in this space.

The acute wall 12 has formed therein a 45 guideway 34 in the present instance shown as in the form of a slot and the plate 30 is provided adjacent its forward end with an upstanding lug 35 engaging in this slot. Adjacent its rear end the plate is provided 50 with a second lug 36 likewise adapted to engage in the slot and when both of the lugs are engaged in this slot the plate is held in such position that engagement of the tooth 32 is so positioned that it clears the teeth 33 and permits movement of the locking plate. When this tooth is engaged with one of the teeth 33 it will be obvious 55 that a forward movement of the plunger will result in the abutment 26 coming into engagement with the rear end of the exten-

sion 31 of the plate 30, movement of the plate 30 being prevented by the tooth engagement. The movement of the plunger 60 enlargement is limited, such limiting occurring before operation of the plunger 70 mechanism. The slot 34 terminates at its rear end in an enlargement 34^a into which the lug 36 of the plate 30 may enter, the enlargement, however, being of such length that its rear end wall 34^b limits the rear 75 movement of the lug 36 at a time when the lug 35 is still engaged in the slot. When the lug 36 is positioned in the enlargement the tooth 32 enters into engagement with the teeth 33 to lock the plate against movement. 80

If a coin be positioned in the channel 22 between the rear end of the plate 30 and the forward end of the abutment 26 of the plunger the forward movement of the plunger will force the coin under the extension 85 31, lifting the same and withdrawing the tooth 32 over the notch and aligning the lug 36 with the slot 34 so that the plunger and plate may be moved forwardly as a unit and the ejector mechanism tripped. When 90 the coin arrives above the slot 21 it will fall from between the plate 30 and abutment 26 through the slot 21 and into a suitable receptacle 37. In order to provide for retraction of the plunger 23 a lug 39 is provided 95 thereon projecting through a slot 40 formed in the acute wall 12 and to which are connected diverging springs 41 having their opposite ends connected with stationary parts of the mechanism. 100

In order to prevent operation of the device by coins of improper denomination, the acute wall 12 is formed with an opening 42, the upper edge of the opening paralleling the upper face of a spacer plate 15 and being spaced therefrom a distance slightly less than the diameter of the coin by which the machine is to be operated. The lower edge of the opening is slightly spaced above the upper face of the plate 15 and likewise parallels the same. Since the wall against which the coin will be thrown because of the inclination of the plates 11 and 12 is provided with this opening any smaller coin passing down the incline will have its upper edge free from engagement with the plate and will accordingly pass through the opening 42 and be discarded. If of the proper denomination it passes downwardly of the upper edge of the plate 15 and between the plate 13 and acute wall 12 between the lower rear end of the plate 15 and the spacer plate 14 and between the plunger and wall 12 coming to rest upon the guide 20 between the abutment 26 of the plunger and the plate 30. If the coin is inserted at the time the plunger is in operating position the same will rest upon the upper surface of the enlargement 26 until the plunger is completely withdrawn, when 130

it will fall into the proper position. Particular attention is directed to the fact that when the extension of the abutment 26 of the plunger is engaged with the rearward extension of the lock plate the space between the adjacent faces of the abutment 26 and the lock plate 30 is greater than the diameter of the coin by means of which the machine is operated. Accordingly this coin 10 is not pinched between these plates and will simply roll ahead of the abutment 26 upon the surface of the spacer 20 until the opening 21 is reached when it will fall through this opening.

15 In the operation of the device the coin is placed in the usual coin receiving slot, indicated at 17, and in passing through this slot rolls upon the upper surface of the plate 15, finally passing, if it be of the 20 proper denomination, through the opening 16 to be disposed between the lock plate 30 and the front wall of the enlargement 26 of the plunger 23. If the coin be of a smaller size than that required the coin will fall 25 from the tip out opening, as hereinbefore explained, and will never arrive at the opening 16 to fall therethrough. With the coin introduced the plunger 23 will be shifted outwardly by engaging the finger in the 30 notch formed at 25 for such engagement and as it moves outwardly the coin will roll upon the upper surface of the plate 20 and in coming into engagement with the finger 31 of the lock plate 13 will elevate the same 35 and pass therebeneath. This elevation will occur at such a time that continued forward movement of the plunger will bring the front end of the abutment 27 into engagement with the rear end of the extension 31 40 so that the lock plate is forced longitudinally. This longitudinal movement is not possible for the reason that the lug 36 is aligned with its channel or guideway 22 of the plate 12 and accordingly continued forward movement may be had. During this 45 forward movement the coin, which because of the spacing of the lock plate 30 and enlargement 26 of the plunger by the engagement of the portions 27 and 31 thereof is 50 not pinched between the lock plate and enlargement, will continue to roll upon the surface of the plate 20 until it comes to the opening 21 at which time it will fall through the opening into the coin drawer. It will, 55 of course, be understood that the ejector or ejector operator 29, as the case may be, will be shifted by the plunger during its movement and such shifting movement will be utilized to eject the goods from the machine. Since this ejection apparatus does 60 not form a portion of the present invention the same is not described or disclosed herein.

It will be obvious that the construction herein described is capable of considerable 65 mechanical alteration and likewise capable

of considerable change in a specific arrangement thereof without in any manner departing from the spirit of our invention. We accordingly do not limit ourselves to such specific structure except as hereinafter 70 claimed.

What is claimed is:—

1. In check control apparatus, a mounting having a channel, a plunger reciprocable within the channel and having an abutment 75 on one side face thereof, a lock slideable between said side face of the plunger and the opposed wall of the channel and normally having engagement with a wall of the channel preventing this movement when engaged by the abutment of the plunger, said lock including a rearward extension engaged and shifted by a coin preceding the plunger and by its shifting releasing the engagement of the lock with said channel wall. 80

2. In check control apparatus, a mounting having a channel, a plunger reciprocable within the channel and having an abutment on one side face thereof, a lock slideable between said side face of the plunger and the opposed wall of the channel and normally having engagement with a wall of the channel preventing this movement when engaged by the abutment of the plunger, 90 said lock including a rearward extension engaged and shifted by a coin preceding the plunger and by its shifting releasing the engagement of the lock with said channel wall, said abutment being provided with a forward extension overlying the rearward extension of the lock when the plunger is advanced into engagement with said rearward extension without the intervention of a coin of the proper denomination and preventing withdrawal of said lock from its engagement with the wall of the channel. 100

3. In check control apparatus, a mounting having a channel, a plunger reciprocable within the channel and having an abutment on one side face thereof, a lock 110 slideable between said side face of the plunger and the opposed wall of the channel and normally having engagement with a wall of the channel preventing this movement when engaged by the abutment of the plunger, said lock including a rearward extension engaged and shifted by a coin preceding the plunger and by its shifting releasing the engagement of the lock with said channel wall, said extension by its engagement with said abutment when the abutment is preceded by a coin maintaining the lock spaced from the adjacent face of the abutment a distance greater than the diameter of the coin and the coin discharge opening formed in the wall of the channel in advance of said abutment. 120

4. In check control apparatus, a mounting having a channel, a plunger reciprocable within the channel and having an abutment 130

on one side face thereof, a lock slideable between said side face of the plunger and the opposed wall of the channel and normally having engagement with a wall of the channel preventing this movement when engaged by the abutment of the plunger, said lock including a rearward extension engaged and shifted by a coin preceding the plunger and by its shifting releasing the engagement of the lock with said channel wall, said abutment being provided with a forward extension overlying the rearward extension of the lock when the plunger is advanced into engagement with said rearward extension without the intervention of a coin of the proper denomination and preventing withdrawal of said lock from its engagement with the wall of the channel, a coin of the proper denomination preceding said abutment engaging said extension and elevating the same into alignment with the forward extension of the abutment, said extensions of said lock and abutment when engaged spacing the adjacent faces of the lock and abutment apart a distance greater than the diameter of the coin.

5. In check control apparatus, a mounting having a channel provided in the wall thereof with a notch, a plunger reciprocable within the channel and having an abutment normally positioned rearwardly of the notch, a lock slideable between the side face of the plunger and the opposed wall of the channel, and arranged in the path of the abutment and having a tooth normally engaged with the notch of the channel wall, said channel having a slot in the wall thereof, a lug on said slot pivotal and slideable in said slot, the slot having an enlarged rear end, a second lug on the lock disposed in the enlarged rear end of the slot when the tooth of the wall is engaged with said notch, the rear end of said lock being engaged and elevated by a coin preceding the abutment and held in such elevated position until the last named lug of the lock is likewise engaged in said slot.

In testimony whereof we hereunto affix our signatures.

LEE ROY SPOONER.
PAUL L. GRAY.
